UNITED STATES PATENT OFFICE.

ROBERT E. WOODSON, OF ST. LOUIS, MISSOURI.

NUT-CRACKING MACHINE.

No. 831,589.

Specification of Letters Patent.

Patented Sept. 25, 1906.

Application filed January 7, 1905. Serial No. 239,989.

To all whom it may concern:

Be it known that I, ROBERT E. WOODSON, a citizen of the United States, residing in the city of St. Louis, in the State of Missouri, have invented certain new and useful Improvements in Nut-Cracking Machines, of which the following is a full, clear, and exact description, reference being had to the accompanying drawings, forming part of this specification.

My invention relates to a machine for cracking edible nuts, and comprises a simple and efficient construction by which the nuts may be rapidly and efficiently cracked in a manner to preserve their kernels in a whole and unmashed condition.

Figure I is a side elevation of my machine. Fig. II is a top or plan view of the machine. Fig. III is a longitudinal section taken on line III III, Fig. II. Fig. IV is a vertical cross-section taken through a part of the machine on line IV IV, Fig. II. Fig. V is an enlarged perspective view of the cam member located within the rotatable jaw-carrying head of the machine. Fig. VI is a section taken on line VI VI, Fig. II, with parts adjacent to said line shown in elevation. Fig. VII is an enlarged cross-section taken through the hollow shaft on which the rotatable jaw-carrying head is mounted and the cam member in said shaft. Fig. VIII is a perspective view of one of the ejectors in the rotatable jaw-carrying head. Fig. IX is an enlarged cross-section taken on line IX IX, Fig. II.

1 designates the bed of my machine, that is provided at its upper side with a table 2. At the forward end of the bed is a pair of uprights 3, and at the rear end of the bed is an arm 4, provided with a journal-box 5. In the journal-box is a power-shaft 6, (see Figs. I, II, and III,) on which is a pulley 7, to which power is suitably applied for the operation of the machine.

8 is a crank-wheel fixed to the power-shaft 6 and having seated therein a wrist-pin 9, to which is connected an adjustable pitman 10.

11 designates a carriage reciprocally mounted upon the table 2 of the machine, so that it may ride longitudinally thereof. The carriage 11 bears boxes 12, and it is fitted to the table 2 by downwardly-extending flanges 13, between which and said table are gibs 14, held by set-screws 15 passing through said flanges.

16 designates a rock-shaft journaled in the carriage 11, and 17 is a toothed segment fixed

to this shaft and having the pitman 10 connected thereto, whereby oscillation of said segment is secured upon the rotation of the crank-wheel 8 to impart rotation to the rock-shaft 16. The rock-shaft also has fixed thereto a rocking arm 18, which is provided with a roller 19, that operates in a pocket 1^a in the bed of the machine. It will be seen that when the rock-shaft 16 is rotated through the medium of the segment 17 the rocking arm 18 is thrown to and fro in the pocket in which it is positioned to impart movement to the carriage 11.

At the end of the carriage 11 is an arm 11', that is equipped with bearing-boxes 20, in which is journaled a rock-shaft 21, having fixed thereto a pinion 22, arranged in mesh with the toothed segment 17, and through the medium of which said rock-shaft is rotated.

23 represents trip-wheels fixed to the rock-shaft 21 and occupying positions above the carriage-arm 11'.

24 designates plungers reciprocally mounted in the carriage-boxes 12 and extending longitudinally of the carriage.

25 represents dogs swingingly connected to the plungers 24 at their rear ends by pivot-pins 26. These dogs oppose the trip-wheels 23, and their free ends are adapted to be engaged by said trip-wheels to cause the wheels to impart swinging movement to the dogs in the manner and for the purpose to be herein-after explained.

27 represents adjustable stops (see Fig. III and dotted lines, Fig. II) that are seated in the rear end of the carriage 11 beneath said dogs 25, and by which the dogs are normally supported. Each of the reciprocating plungers 24 is provided with a longitudinal slot 24'. (See Figs. I and IV.)

28 is a post fixed to the carriage-supporting table 2 of the machine and extending upwardly through a slot 11^a in the carriage 11 to permit of the reciprocation of said carriage with respect to said post.

29 represents arms extending laterally from the post 28 and through the slots 24' in the plungers 24. These arms support ejectors 30, that extend forwardly therefrom through said plungers.

31 represents nut-cracking jaws carried by the plungers 24 at their forward ends and through which the ejectors 30 operate, as seen in Fig. III.

32 represents stop-pins that are inserted

- through perforations 24^a in the plunger 24 forward of the arms 29, that operate in said plungers and which are adapted to strike against said arms when the carriage 11 is reciprocated rearwardly to stop said plungers. A plurality of the perforations 24^a are preferably provided, as seen in Fig. II, in order that the stop-pins may be variably seated in the plungers. In the top of each plunger 24 is a recess 24^b, (see Figs. III and IX,) that is adapted to receive a spring-pressed retaining-pin 33, slidably positioned in housings 34, set into one of the bearing-boxes 12, through which the plunger 24 operates. These spring-pressed retaining-pins serve to hold the plungers from accidental displacement while in their rearmost positions in order that they may be maintained in fixed positions until positively actuated in the manner to be hereinafter explained.
- 35 designates an eccentric fixed to the power-shaft 6 and surrounded by a band 36, that operates thereon.
- 37 is a pitman connected to the band 36 and extending forwardly therefrom.
- 38 designates a cam member that is slotted transversely to provide cams 39. (See Figs. III, V, and VII.) This cam member, which is in the form of a rod, is mounted in the uprights 3 at the forward end of the machine and is held from rotation by a clamp 40, fixed to the cam member and also to the adjacent upright, as seen in Figs. I and II, the method of securing the clamp to said parts being preferably that of set-screws 41 and 42.
- 43 is a hollow shaft rotatably mounted upon a cam member 38 and loosely seated in the uprights 3. This hollow shaft is provided with apertures 44, (seen most clearly in Fig. VII,) that are located in alinement with the cams 39. The shaft extends through one of the uprights 3, and fixed to the extreme end of said shaft is a crank-arm 45, to which the pitman 37 is loosely fitted.
- 46 is a ratchet-wheel fixed to the hollow shaft 43 adjacent to the crank-arm 45, and 47 is a spring-pressed pawl carried by the crank-arm and adapted to engage said ratchet-wheel for the purpose of imparting rotation to the hollow shaft when said crank-arm is rocked to and fro through the medium of the pitman 37.
- 48 designates a rotatable jaw-carrying head mounted upon the hollow shaft 43.
- 55 This head is provided with a plurality of nut-receiving pockets 49, that are adapted to move in a path of travel directly in front of the nut-receiving jaws 31, carried by the reciprocating plungers 24.
- 60 50 represents nut-cracking jaws set into the rotatable head 48 at the rear ends of the pockets 49 and provided with central apertures.
- 51 represents ejectors having their outer portions slidably positioned in the apertures

in the jaws 50 and having their inner ends seated in apertures 44 in the hollow shaft 43. The ejectors are provided with annular ribs 52, located thereon at the rear of the jaws 50, and they are surrounded by retracting-springs 53, which serve to hold the inner ends of the ejectors pressed against the cams 39 of the fixed cam member 38. These cams are located at the bottom of the cam member, as seen in Figs. III and VII, so that the inner ends of the ejectors may ride in the slots in the cam members at the locations of the cams without being pressed outwardly, while each pocket 49 of the rotatable jaw-carrying head is approaching the opposing plunger-carried jaw 31 and whereby the cam may act to force the ejector outwardly immediately after a nut has been cracked between said jaws and the pocket containing the nut is rotated downwardly and away from the opposing jaw 31.

54 designates a gage-finger carried by the forward box 12 of the carriage 11 and which is adapted to enter into one of the bores 48', located between the nut-receiving pockets 49, each time that the carriage 11 is reciprocated forwardly and the rotatable head 48 is rotated to bring the nut-receiving pockets into alinement with the plunger-carried jaws 31. The gage-finger by entering said bore 48' serves to center the pockets 49 with respect to the plunger-carried jaws, so that said plunger-carried jaws may enter the pockets accurately to exert pressure against the nuts previously deposited in the pockets.

The operation of my machine is as follows: The power-shaft 6 being put into motion, power is communicated therefrom through the crank-wheel 8 and pitman 10 to the segment 17 to rotate the rock-shaft 16 and impart reciprocation to the carriage 11, due to the operation of the crank-arm 18 in the bed-pocket 14. As the segment 17 oscillates it imparts rotation to the rock-shaft 21 through its intermeshing engagement with the pinion 22 thereon and the trip-wheels 23 are thereby rotated. At the same time that the parts mentioned are actuated in the manner stated rotation is imparted to the jaw-carrying head 48 through the medium of the eccentric 35, carried by the power-shaft, the band 36 operating thereon and the pitman 37 having driving engagement with the shaft 43, that carries the jaw-carrying head 48, through the medium of the crank-arm 45, pawl 47, and ratchet-wheel 46. The nuts to be cracked are introduced into the pockets 49 of the jaw-carrying head, and as said head is rotated the pockets are in turn brought into alinement with the plunger-carried jaws 31, at which time the ejector in each advanced jaw 50 is in reeded position. The driving members of the carriage and rotatable jaw-carrying head are so actuated that the carriage will move forwardly to bring the plunger-carried jaws 31

31 into juxtaposition with the alining nuts receiving pockets of the rotatable head at the same time that said pockets are moved into horizontal position. As the carriage 11 continues to move forwardly the retaining-pins 34 cause the plungers 24 to be carried therewith, and the jaws 31 by pressing against the nuts in the pockets 49 cause said plungers to stop until the dogs 25 come into engagement with the trip-wheels 23, the path of rotation of which is upwardly and forwardly. The plungers are thereby again moved forwardly momentarily due to the engagement of the dogs with the trip-wheels, and during such movement of the plungers the nuts are cracked between the jaws 31 and 50. Immediately after the nut-cracking action takes place and before there is any possibility of the nuts being mashed the trip-wheels 23 act to swing the dogs 25 upwardly, thereby relieving the plungers of pressure. The cracking action ceases, and as the driving parts continue to operate retrograde movement is imparted to the carriage, and the rotatable jaw-carrying head is rotated, so that the nuts in the pockets 49 may escape therefrom, their escape being facilitated due to the actuation of the plungers 51, to which outward reciprocation is imparted by the cams of the cam member 38, against which said plungers ride. During the rearward movement of the carriage the ejectors 30 operate through the jaws 31 and serve to force any particles of shell from said jaws, and when the stop-pins 32 are brought into engagement with the ejector-carrying arms 29 the plungers 24, in which said pins are seated, are held stationary, thereby carrying the dogs 25 away from the trip-wheels 23, so that they are out of contact therewith and rest in alinement with the plungers ready for the next nut-cracking action. Upon the further rearward movement of the carriage the retaining-pins 33 enter the recesses 24^b in said plungers and serve to retain them from movement relative to the carriage until the nuts stop the plungers and the dogs again engage the trip-wheels and are positively actuated, thereby providing for the accurate positioning of the jaws 31 with respect to the opposing rotatable head-carried jaws. The strength of nutshells varies greatly, and it is for this reason that I provide the adjustable stops 27, located beneath the dogs 25, and which limit the downward movement thereof. When these stops are adjusted upwardly, the downward movement of the dogs is lessened, so that there will be necessarily only slight travel of the dogs in the nut-cracking action when they are operated upon by the trip-wheels, and the plungers will be actuated more quickly in cracking thin-shelled nuts. When the stops are lowered, a greater movement of the dogs is necessary, and consequently greater pressure will be exerted against the nuts before the dogs move out of

engagement with the trip-wheels, and thick-shelled nuts may be cracked with the same efficiency as thin-shelled ones.

I claim as my invention—

1. In a nut-cracking machine, the combination of a jaw, a reciprocatory plunger provided with a jaw opposing said first-named jaw, and means for imparting forward thrust to said plunger toward said first-named jaw; said means comprising a vibratory trippable member and a rotatable trip member serving to actuate said trippable member; one of said members being carried by said plunger and the other member being mounted independent of said plunger, substantially as set forth. 70

2. In a nut-cracking machine, the combination of a jaw, a reciprocatory plunger provided with a jaw opposing said first-named jaw, and means for imparting forward thrust to said plunger toward said first-named jaw; said means comprising a vibratory trippable member carried by said plunger, and a rotatable trip member arranged in the path of travel of said plunger to engage and actuate said trippable member, substantially as set forth. 85

3. In a nut-cracking machine, the combination of a jaw, a reciprocatory plunger provided with a jaw opposing said first-named jaw, and means for imparting forward thrust to said plunger toward said first-named jaw; said means comprising a dog pivoted to said plunger, a rocking trip member arranged in the path of travel of said plunger adapted to engage said dog, and means for operating 95 said rocking member, substantially as set forth. 100

4. In a nut-cracking machine, the combination of a reciprocatory carriage, a jaw, a plunger arranged to reciprocate on said carriage and provided with a jaw, means for yieldingly holding said plunger against reciprocation relatively to the carriage, and means on the carriage for imparting forward thrust to said plunger toward said first-named jaw, substantially as set forth. 110

5. In a nut-cracking machine, the combination of a reciprocatory carriage, a jaw, a plunger arranged to reciprocate on said carriage, and provided with a jaw, means on the carriage for yieldingly holding said plunger against reciprocation relatively to the carriage, and means for imparting forward thrust to said plunger toward said first-named jaw; said last-named means comprising a 115 trippable member carried by the plunger, and a trip member carried by the carriage, substantially as set forth. 120

6. In a nut-cracking machine, the combination of a reciprocatory carriage, a jaw, a plunger arranged to reciprocate on said carriage and provided with a jaw, a yielding retaining-pin carried by said carriage and engaging said plunger to hold it against reciprocation relatively to the carriage, and means 125 130

for imparting forward thrust to the plunger toward said first-named jaw, substantially as set forth.

7. In a nut-cracking machine, the combination of a reciprocatory carriage, a jaw, a plunger arranged to reciprocate on said carriage and provided with a jaw, a spring-pressed retaining-pin carried by said carriage and arranged in engagement with said plunger to hold it against reciprocation relatively to the carriage, and means for imparting forward thrust to said plunger toward said first-named jaw; said means comprising a dog pivoted to the plunger and a rocking trip member carried by the carriage, substantially as set forth.

8. In a nut-cracking machine, the combination of a jaw, a reciprocatory carriage, a reciprocatory plunger mounted in said carriage, a trippable member carried by said plunger, a trip member carried by said carriage for engagement with said trippable member, means for driving said trip member, a stop seated in said plunger, and a fixed support with which said stop engages to hold said plunger and cause separation of said trippable member and said trip member upon reciprocation of said carriage.

9. In a nut-cracking machine, the combination of a rotatable head, means for rotating said head, a series of jaws carried by said head, a reciprocatory ejector in each of said

jaws, reciprocatory means provided with jaws opposing said head, means for reciprocating said jaw-carrying means, and an ejector mounted in each of said last-named jaws and held from reciprocation therewith. 35

10. In a nut-cracking machine, the combination of a cam member, a hollow perforated shaft fitted to said cam member, a rotatable 40 jaw-carrying head carried by said shaft, means for rotating said shaft, jaws carried by said rotatable member, ejectors seated in said jaws and extending through the perforations in said shaft into bearing with said cam 45 member, and means opposing said head between which and the head-carried jaws the nuts are cracked.

11. In a nut-cracking machine, the combination of a jaw, a reciprocatory carriage, a 50 plunger reciprocally mounted in said carriage, a trippable member connected to said plunger, a trip member carried by said carriage and arranged to be engaged by said trippable member to impart forward thrust to said plunger, 55 a stop seated in said plunger, and means supported independently of said carriage with which said stop engages to hold said plunger from rearward reciprocation and separate said trippable member from said trip member.

ROBT. E. WOODSON.
